4 Claims. (Cl. 40—130)

1
This invention relates generally to illuminated signs, and relates more particularly to signs of the edge-lighted type utilizing transparent and translucent materials such as plastics.

It is an object of the invention to provide devices of this character wherein great diversity and control of optical effects may be produced.

Another object of the invention is to provide a panel of suitable characteristics in which sign characters, such as letters, numerals and the like, may be variously embedded to produce various effects. For example, the sign characters may be wholly embedded in the panel. Thus, by removing the sign characters or decorative features from contact with the air, and embedding them within a substantially transparent block or panel, the basic means is provided for the control and exploitation of differences in color, degree of translucency and refractive index, for the purpose of developing a great many different optical effects. The advantages of embedding the sign characters and figures results in a high degree of control of the optical effects desired, particularly as regards those effects resulting from the combination of materials of different as well as identical indices of refraction.

Further advantages reside in the economical utilization of the light entering the panel from the edge resulting from the property of total internal reflection, a more even illumination of the sign characters, also owing to the effects of the total internal reflection of light, and the enhanced effect on the appearance of the sign characters when seen through a refractory transparent medium. Other effects may also be secured by but partially embedding the sign characters or figures in the panel.

Still another object of the invention is the provision of a device of this character wherein additional effects may be produced by roughening certain surfaces of either the panel or the sign characters, or both.

A further object of the invention is to provide a device of this character wherein still additional effects may be produced by special treatment of certain surfaces such as the rear surface of the panel, so as to provide a "back drop" for the sign characters and the like.

A still further object of the invention is to provide a device of this character wherein an attractive three-dimensional spacious effect is produced.

One of the advantages of embedding the sign characters in the panel is that it isolates such characters from dirt and the like, so that the sign is easily cleaned and polished, and may be

rebuffed should that be necessary after a period of use.

In many edge-lighted signs now in use the illumination is intense over the lower portion of the sign characters but is weak over the upper portion, or vice versa, and it is therefore another object of the invention to provide a device of this character wherein there is relatively even illumination of the sign characters. One factor in securing such even illumination is the characteristics of the sign characters themselves which readily transmit light to all parts thereof. Another feature of the invention which aids in effecting even illumination of the sign characters is the use of a plurality of light sources. For example, the panel is illuminated from a plurality of sides, as from the top and bottom, and the panel is provided with rearwardly extending portions having the top and bottom edges curved so as to illuminate the sign characters evenly.

Still another object of the invention is to provide a device of this character wherein the illuminated parts of the device differ optically from each other in some respect, so as to afford contrast and variety.

A further object of the invention is to provide a device of this character wherein the sign characters are fully visible throughout a wide range of viewing positions.

A still further object of the invention is to provide a device of this character wherein sign characters and the like, having various different optical characteristics may be employed within the same sign.

A still further object of the invention is to provide a device of this character wherein sign characters may be so disposed that some of said characters are in front of others, while all said characters are visible in their entirety.

A still further object of the invention is to provide a device of this character, wherein actual objects, or facsimile objects, may be embedded in the panel, such as, for example, bottles, etc.

Further objects and advantages of the invention will be brought out in the following part of the specification.

Referring to the drawings, which are for illustrative purposes only,

Fig. 1 is a perspective view of a sign embodying the present invention;

Fig. 2 is a sectional view taken on line 2—2 of Fig. 1;

Fig. 3 is a fragmentary sectional view showing an alternative arrangement of the panel and sign characters;

Fig. 4 is a perspective view of a sign embodying an actual object embedded in the panel; and

Fig. 5 is a perspective view of an alternative arrangement of the invention.

Referring to Fig. 1, reference numeral 10 indicates a housing for supporting a transparent enclosing block or panel, indicated generally at 11, which is illuminated by one or more suitable surfaces of light within the housing, as will be more fully described hereinafter.

The housing comprises a front wall 12, side walls 13, a top wall 14, a back wall 15, and a bottom wall 16, the latter extending forwardly at 17, of the front wall 12, to prevent forward tilting of the sign.

The panel 11 has rearwardly turned portions 18 and 19 at the top and bottom respectively, said portions extending through openings provided therefor in the front wall 12. It is to be understood, of course, that the panel or block 11 is of transparent material such as, for example, a clear plastic, or at least is substantially transparent.

Means for securing the free ends of the flanges or parts 18 and 19 within the housing comprise brackets 20 and 21 located above and below the upper extension 18, and brackets 22 and 23 disposed above and below the lower extension 19. These brackets extend longitudinally of the housing and are secured to the interior thereof by any suitable means such as welding, soldering, or the like.

As shown in Fig. 2, there is a source of light for each of the extensions, there being a source of light 24 aligned with the upper extension, and a second source of light 25 aligned with the lower extension. These sources of light may be of any suitable character, although they are shown as fluorescent tubes, which extend longitudinally of the housing behind the respective extensions 18 and 19. These light sources are usually white but can be of any other desired color, or one may be of one color and the other of a different color. If desired, in order to intensify the light reflected into the panel 11, reflectors 26 and 27 may be provided about the tubes 24 and 25 in such a manner as to reflect the light from said tubes into the adjacent tubes of extensions 18 and 19. The reflectors may be of any suitable type, and are secured within the housing by any suitable means, not shown.

The light enters the respective extensions through the surfaces 28 and 29 respectively, and is deflected from the curved longitudinal edges 30 and 31 respectively, so as to direct said light throughout the panel. The radii of the curved edges 30 and 31 are such as to internally reflect the light and not allow it to escape, and the illumination within the panel 11 is the result of the total internal reflection of light from said sources.

The rear surface of the panel may be treated in a variety of ways, but in Figs. 1 and 2 said surface is polished and buffed. Likewise, the face 32 of the panel is buffed and polished to a high degree so that it will be as invisible as possible, will internally reflect the light, and will pass the light reflected from the sign characters. When the sign is seen in complete darkness, the face of the panel is completely invisible. However, when the sign is seen in semi-darkness or in light, the face reflects a certain amount of external light. However, these reflections can be substantially eliminated by the application of one of the glare and reflection-killing micro-films of known character.

It is to be understood that the term "sign characters" as used herein, is intended to mean let-

ters, numerals, emblems, sculpture, objects d'art, decorative figures, facsimile objects, actual objects, and all other usages where the principles enumerated herein find application. The purpose of the above wording is to emphasize the fact that the essence of this invention—light reflecting, transmitting and absorbing materials embedded within a substantially transparent panel and illuminated—is applicable in many different fields.

As shown in Figs. 1 and 2, certain of the sign characters, indicated generally at 35, and comprising the letters "ORO" extend in relief from the rear surface of the enclosing panel 11 in the direction of the face 32, that is, the rear surfaces of these characters share a common plane with the rear surface of said panel. These letters possess optical properties different from the optical properties of the panel, and such properties may relate to color, degree of transparency, and/or refractive index, so that they will be distinguishable when the device is illuminated. Embedded completely within the panel are additional sign characters, indicated generally at 36 and comprising the words "For quality." These words are located in front of the letters "ORO." The words "For quality" are set off from the characters behind them and also from the rear surface of the enclosing panel so that they appear to be suspended in space. Thus the illusion of spaciousness within the panel is heightened. The words "For quality" can, if desired, be more transparent than the letters "ORO" so that the latter may be seen in their entirety simultaneously with the former.

It is to be understood that the sign characters 36 possess optical properties which are of such character as to make them readily distinguishable in connection with the optical properties of the panel (which is essential to the invention) and the characters 35 (which is desirable though not necessary).

Embedded within the panel is also a base for the characters "ORO," said base being indicated generally at 37. This base has no structural purpose in the sign because in fact all sign characters are held firmly in place by virtue of being embedded in the panel. Rather its function in this sign is decorative in seeming to support the letters "ORO" and providing a front face 36 which has the words "Why not try the best?" inscribed thereon, as indicated at 38. That is, the base is non-functional from the structural point of view, but has an aesthetic function. The base 37 should be extremely transparent so as to permit the maximum passage of light therethrough from the lower source of light 25. This is desirable in view of the fact that the base 37 is located adjacent the lower end of the panel 11 and in the path of light passing through the extension 18 and into said panel.

The characters 38 are on the front surface of the base 37 and, in contrast to the other sign characters above described, the effect is two-dimensional rather than three-dimensional. They may be applied in the manner commonly used in the coloring of indicia or instrument dials. The differences between these sign characters and those found in ordinary dials is that the former are completely embedded and insulated from the air, whereas the latter are not.

In the present arrangement the sign characters "Why not try the best?" are illuminated mainly by conventional transmitted light and only partially by edge lighting. This is due to

the fact that the source of light enters the panel directly behind these letters and they are seen against said source of light. This type of illumination gives a distinctly different appearance to the sign characters than where they are edge-lighted.

It is to be understood that in a sign of the present character the enclosing panel 11 should, in general, be more transparent than the most transparent sign character or figure within it, otherwise it would mask out some or all of said characters. Moreover, for the most striking results, sign characters superimposed in front of other characters should be more transparent than the latter.

Of course, the sign characters may be of various types and may have various characteristics. For example, there may be various optical characteristics which the materials may have for the purposes of this invention. These optical characteristics can be listed as color, degree of translucency, refractive index and an important fourth characteristic representing combinations of the former three to form patterned, textured and mottled effects. These latter in most cases result from the mixing and incomplete fusion of materials of different colors, and/or degrees of translucency, and/or indices of refraction. The materials which are used and the manner in which they are mixed determine the particular pattern, or texture, in any given instance.

Regarding the material embedded within the enclosing block, several categories have been established. The first is best described as constituting a thin interlayer, or what can be conceived as an embedded surface. This embedded surface is (1) disposed two-dimensionally (on a plane) within the panel, or (2) extends three-dimensionally within it. Whether disposed two-dimensionally or three-dimensionally within the panel, it is always a thin interlayer of non-transparent—although preferably near-transparent—light reflecting material. In the second category the material delineating the sign character extends three-dimensionally through the mass of the sign character. Some examples will make these distinctions clear. If a transparent methacrylate letter is surface dyed and then embedded within a methacrylate block, there is a visible interlayer; this represents the first category. On the other hand, the letter may be formed from a sheet of methacrylate which, in manufacturing has been caused to be dyed all the way through its mass; this represents the second category.

Taking the sign characters 35, the surfaces may be colored and they are then seen as an interlayer of color; or if they are colored all the way through their mass, they are seen by virtue of such coloring. Or they may have their surfaces 40 slightly more opaque than the panel 11 and are rendered visible by virtue of such degree of opacity. Further, these characters may be more opaque than the panel through their mass, and rendered distinguishable in this way.

A further alternative arrangement is to have the interlayer 40 of a different refractive index than that of the enclosing panel 11; or it may be comprised of a material of a different refractive index than that of the panel and extending three-dimensionally through the mass of said character. Or the same purpose (i. e., distinguishing the sign character from the panel and rendering it visible) can be achieved by a mottled interlayer at 40, or this same mottled effect can be translated into a three-dimensional form and

extend through the mass of the sign character. It is, of course, to be understood that the coloring, translucency and other characteristics above discussed may also extend only over a part of the surfaces of the sign characters or only partially through their mass, achieving in this way a graduated effect.

Whether the sign characters 35 are made distinguishable from the panel and visible to the observer by an interlayer represented by 40 or by virtue of a similar optical treatment extending through the mass of the sign characters is not so important where the result is achieved through differences in color, translucency or refractive index, either singly or in combination.

For example, if the sign characters 35 are red in color it is difficult for the spectator to ascertain whether this coloring matter extends only over the surface of the characters or whether it extends through their mass—this in spite of the fact that there exists an actual difference in effect between the one and the other (i. e. a sign character colored through its mass absorbs more light). Where mottled effects are resorted to, however, the case is different. Mottled effects, it will be recalled, are the result of mixing materials of different optical characteristics in such a way that complete fusion does not result. In this instance it is normally not difficult for the spectator to ascertain whether the mottled effect is an interlayer within the panel or extends through the mass of the sign character. The importance of these mottled effects to the present invention justifies the emphasis which has been assigned to the differences between the aforementioned categories. Three-dimensional textures and mottled patterns are among the most beautiful effects characteristic of this sign.

Let us say, for instance, that two transparent materials of different indices of refraction are mixed together. One might suppose, because both materials are transparent, that they will remain invisible within the panel. However, this is not the case, at least when mixed in such a way that complete fusion is not the result. In this instance discrete minute areas of one material are adjacent to the other. At the interface where the two materials conjoin a reflection is established. Multiply these points of reflection by many thousands, insure there is a correct density of these reflections per unit area, and the result is a flowing, apparently homogeneous, mass of luminous material. When utilized this effect accounts for the special luminosity of the sign characters in the present sign. Moreover, it represents the principal means whereby white and all color tints deriving from white are achieved.

It has been previously said that the sign characters, even though colored, should preferably remain as transparent as possible. There are several reasons for this. For one thing, a sign character which is dark in color is correspondingly more opaque. In other words, the ratio of light absorption to light reflection and transmission is weighted on the side of absorption, i. e. the sign character is reduced in luminosity. Because light transmission and reflection are so preferred over absorption dyes are normally, though not invariably, used in preference to pigments as coloring matter. Unfortunately, there is no such thing as a white dye. This explains the importance of the special luminous effect described in the previous paragraph.

It is not sufficient simply to create a three-dimensional, mottled texture using transparent

materials of different indices of refraction to obtain the aforesaid luminous effect (which might be described as a multiplied micro-point reflection effect), at least if the most intense luminosity is to be had. The materials chosen must be right, not only as regards respective indices of refraction but also as regards the surface tension established between the two. The number, size and positioning of the minute areas or points within the enclosing "vehicle" must be correctly calculated for maximum reflection. For example, if the sign character is too densely packed with these reflecting points or areas most of the light is reflected back out before it penetrates the sign character; i. e. it is excessively opaque. In this instance the sign character is luminous around the edges but dull in the middle portions. On the other hand, if there are not a sufficient number of these reflecting areas or points, the luminosity is reduced and the effect is comparable to that of scattered stars against a dark field. Then again, the smaller the points or areas of reflection the more conducive to a homogeneous, glowing effect reminiscent of neon gas.

What has been said in preceding paragraph pertaining to the word "ORO" also applies to the words "For quality," it being understood that in determining the specific treatment of these sets of sign characters the two at least differ optically in some respect so as to afford contrast and variety. For example, the words "For quality" may be very transparent so that the word "ORO" can be seen through them allowing all letters to be seen simultaneously. It might be suggested that only the surfaces be colored, in contrast to coloring through their mass because the latter arrangement tends to absorb more light. Thus, the sign characters comprising the words "For quality" may be unsaturated in color (very little color, i. e. a light shade) and therefore would be very transparent (as opposed to translucent or opaque) and of the same refractive index as that of the enclosing panel 11 so there would be no glare or reflections to cut down transparency. In contrast, the word "ORO" may be deeper in color, luminous owing to the micro-point reflection effect described in the previous paragraph (perhaps combined with a three-dimensional texture), relatively translucent, and comprised of materials of different refractive indices than that of the panel 11.

One of the sub-categories previously described—an embedded interlayer disposed on a plane—applies to the sign characters "Why not try the best?" because these are two-dimensional in every sense. However, like the three-dimensional sign characters these two-dimensional letters can be saturated or unsaturated in respect to color; transparent, translucent or opaque; of the same or different indices of refraction from the panel 11; or they may be mottled in the aforesaid manner.

By removing the sign characters or decorative figures from contact with the air and embedding them within a substantially transparent block the basic means is provided to control and exploit differences in color, translucency and refractive index for the purpose of developing an indefinite repertory of optical effects. The advantages of embedding can be summarized as (1) resulting in a high degree of control of the optical effects desired, particularly as regards those effects (reflections and their absence) resulting from the combination of materials of dissimilar

as well as identical indices of refraction, (2) an economical utilization of the light entering the block from the edge resulting from the property of total internal reflection, (3) a more even illumination of the sign characters also owing to the effects of the total internal reflection of light, (4) a more even illumination of the sign characters owing to the control which is exercised over the indices of refraction of the embedded sign characters and the panel, (5) the desirable effect on the appearance of the sign characters when seen through the refractory, transparent medium, (6) providing a transparent, invisible superstructure, or support, for the sign characters holding them in a proper position relative to the source of illumination and to the other elements constituting the over-all design of the sign, (7) providing a transparent, invisible superstructure, or support, for a backing or "backdrop" for the sign characters, and (8) providing a compact, durable, easily cleaned, easily maintained protective housing for the sign characters.

In the preceding paragraph summarizing the advantages of enclosing the sign characters in a transparent panel one point was not listed because it pertains to the manufacture of the sign—a subject which has not previously been mentioned. To an uninformed observer it would appear that the sign characters are manufactured apart from the enclosing panel and only subsequently embedded within it. But as a matter of fact the procedure may involve molding the enclosing panel first with the sign characters (or more precisely, the shapes of the sign characters) already a part of the panel as deep recesses in its rear surface. Then, with a subsequent molding operation, the recesses are filled in solid to produce the result seen by the observer. When this method is followed the panel is rightly conceived as a necessary antecedent to the manufacture of the sign characters themselves. In effect the panel itself is a mold in which the light reflecting materials comprising the sign characters are formed.

While the transparent panel could, if desired, be made of almost any transparent material, plastics, such as polystyrene and methacrylate have been found highly desirable. Where thermoplastics such as these are used, injection molding is the most practical of the various molding techniques available. Without going into detail regarding the methods envisaged for manufacturing the sign, some discussion of the subject will serve to clarify certain features of the sign itself.

For example, if it is intended that the enclosing panel be slightly colored, let us say tinted throughout its mass, molding powder is selected of the proper color, care being exercised to insure that the color is not so dark that it absorbs too much of the illumination or masks out the sign characters. If it is desired that the sign characters are seen by virtue of a light reflecting interlayer within the panel the recesses are sprayed, or otherwise coated, with a suitable material. The panel is then inserted in a mold and the recesses filled in solid with a material of the same characteristics as those of the panel itself. As an alternative the recesses can be left uncoated and filled in with a colored plastic; or as a further alternative the two methods can be combined.

Let us say, on the other hand, that the sign characters are to be rendered visible by virtue of

a three-dimensional interlayer which is mottled. In this case the recesses are sprayed with a special mixture consisting of two or more light reflecting insoluble, incompatible materials. The failure of these materials completely to merge results in patterns and mottled effects which are very effective, especially when seen under the conditions of edge lighting. By combining materials of different chemical composition, colors, degrees of translucency, and refractive indices a great variety of effects can be secured.

Or let us say that the recesses are sprayed with a special mixture consisting of minutely granulated transparent particles of a given refractive index immersed in a vehicle of a different refractive index—a vehicle, moreover, in which they are insoluble. Being insoluble in said vehicle the surface irregularities of these minute granules are preserved and being immersed in a surrounding medium of a different index of refraction they are light reflecting. The recesses being filled in with a material of optical characteristics identical with those of the panel, and the panel being edge lighted, the sign characters are rendered visible by virtue of this "encased" frosted effect (which, be it said in passing, is in effect the "interlayer" counterpart of the micro-point reflection effect). Somewhat the same result may be obtained by roughening the recesses with sand blasting apparatus, coating them with a material of a different refractive index from that of the panel and in which the material comprising the panel is insoluble, and filling in the recesses are previously described. The above are methods of achieving whiteness and luminosity in the sign characters and in this respect have the same function as the micro-point reflection effect.

Where it is desired that a mottled effect extend three-dimensionally through the mass of the sign character a different procedure is followed. In this instance the recesses in the rear surface of the panel are left uncoated and a plastic compound with which the recesses are filled is of a special character. In other words, the mixture which is fed into the hopper of the injection molding machine consists of at least two different materials, or if the mixture consists of the same plastic material there must at least be a difference as regards color and/or degree of translucency. For instance, a given mixture might consist of three constituents, all of them the same methacrylate plastic: (1) 50% transparent powder, (2) 30% colored powder and (3) 30% a powder which is somewhat more opaque than both of the preceding. When the granules are heated in the heating cylinder of the molding machine they soften and by action of a ram are forced into the mold cavity and finally into the recesses in the rear surface of the panel. Complete mixture of the three constituent materials does not occur, however, because they never become sufficiently liquid to fuse. Rather, the result is a three-dimensional mottled effect comprised of transparent, translucent and colored areas. By varying the composition of the mixture as regards the type, size, proportion and number of the constituent granules an infinite number of effects can be obtained.

The micro-point reflection effect, as regards technique of manufacture and in other respects as well, is related to the immediately preceding. What is required in this instance, however, is a mixture of at least two substantially transparent materials of different indices of refraction. It

will be recalled that the micro-point reflection effect results where minute areas, or points, of a given index of refraction are surrounded by a vehicle of a different refractive index and are illuminated. While a certain amount of luminosity will always result from this combination maximum reflection is contingent upon (1) the nature of the materials comprising respectively the embedded minute areas and the surrounding vehicle, (2) the respective indices of refraction of the embedded areas and the vehicle, (3) the size of the embedded areas, (4) their position, and (5) their density relative to the surrounding vehicle. Control of these in the molding operation is obtained by a correct determination of (1) the types of materials making up the mixture, (2) the proportion, or ratio, by weight of these constituent materials, (3) the size of the granules of the respective constituent materials, and (4) general molding conditions.

For example, as regards the types of materials used, one might be a transparent, thermoplastic material of a given index of refraction and the other a transparent thermosetting plastic of another index of refraction, keeping in mind that the granules of thermosetting material are to comprise the minute, light reflecting areas within the vehicle which is made up of the thermoplastic material. Because the thermosetting granules do not soften under the effect of heat they maintain their identity and shape during the injection operation. This introduces an added element of control into the molding operation—a control which is apt to be materially lessened when two thermoplastic materials are used. Then again, because a correct density of the reflecting points, or areas, within the vehicle is necessary if maximum reflection is to result, the proportion, or ratio, in which the respective sets of granules are mixed is of utmost importance. Importance must also be attached to the absolute and relative sizes of the granules comprising the mixture. It will be recalled that the micro-point reflection effect is most effective where the reflecting surfaces are extremely minute and contribute to an effect of a glowing such as neon gas. These reflecting surfaces can be no smaller than the granules of which they are comprised.

In the preceding the micro-point reflection effect is described as resulting from the co-molding of two or more types of granulated plastic materials. When this method is followed any given reflection results from the conjoining of two solid materials of different refractive indices, said reflection taking place at the interface between these materials. Reflection can also result, however, at the interface between a gas and a solid, let us say, for example, where air and a plastic material conjoin. This can be achieved by heating transparent plastic granules of homogeneous composition in a mold and compressing them, insuring that the pressure is not so excessive that all the air is driven out. In other words, if the exact amount of heat and pressure are applied minute pockets of air remain trapped within the sign character. Reflections are established where the air pockets and surrounding plastic vehicle conjoin. The effect is substantially the same as that previously described. While it is possible to exercise this pressure control where compression molding technique is utilized, it is less feasible when injection or transfer molding operations are used. The desired effect may also be secured by having reflecting areas consist of minute pockets of a liquid mate-

rial embedded within a solid vehicle, or even that the reflecting areas might consist of discrete solids immersed in a liquid, or solids immersed in a gas. An example of the latter might be something on the order of spun glass stuffed or blown into the recesses of the transparent panel.

It was previously said that embedding the sign character within the enclosing panel permits control of the refractive index of the sign character relative to that of the panel. These refractive indices may or may not be the same. If they are identical, no glare effects emanate at the interface between the sign character and the enclosing panel. On the other hand, if the refractive indices vary the contrary holds true. When the two refractive indices are different and result in glare effects, these latter are not uniformly distributed over the entire surface of the sign character; rather they are localized at certain points. This is held to be a limitation characteristic of many plastic illuminated signs now in use—a limitation which results from the fact that the light does not approach every part of the surface of the sign character with the same angle of incidence. In these cases, any particular pattern of light reflection is determined by the conformation of the interface (i. e. the specific shape of the sign character) relative to the angle of incidence of the illumination. In so far as the manufacturer of the sign character determines its shape it indirectly determines the pattern of light reflections which result. In actual practice, however, the latter is largely an unforeseen result and essentially accidental.

Taking, for instance, the letter "R" in the word "ORO": if this letter is comprised of a material of a different refractive index from that of the panel certain parts of its surface will be subject to glare and will thus be rendered visible; the remaining parts, however, will remain invisible. This is owing to the fact that, when the sign character and panel are of different indices of refraction, total internal reflection takes place within the sign character as well as within the enclosing panel. In other words, the interface between the sign character and the panel exerts the same action on the impinging light as the interface between the panel and the surrounding air. Assuming the medium in which the sign character is immersed is of a different refractive index than that of the sign character it is more or less irrelevant, considered from the standpoint of appearance, whether this medium be a solid, such as the plastic of the enclosing panel, or a gas, such as the atmosphere. This is assuming, of course, that illumination in both instances is by total internal reflection.

When a sign character is comprised of the micro-point reflection effect extending substantially through its mass it is again more or less irrelevant, from the standpoint of appearance whether said sign character is immersed in a solid or gaseous medium. Assuming, at least, that the medium is of a different refractive index than the predominant material of the sign character, with the resulting localized glare effects, the latter are overwhelmed by the prevailing high luminosity of the letter as a whole. In other words, the reflections at the interface conjoining the sign character and the panel are invisible and thus neither augment nor lessen the clear definition of the sign character. Considered from this point of view a sign character comprised of the micro-point reflection effect, or

its variations, can advantageously remain unembedded—providing, of course, that the light source is never seen directly. For this reason sign characters comprising the micro-point reflection effect, and its variations, are considered within the scope of this invention even when disassociated from the enclosing panel as shown in Fig. 5. In this figure reference numeral 50 indicates the housing containing the illumination unit. A base 51, for the sign characters or letters "ORO" indicated generally at 52, is shown disposed on the housing, said sign characters "ORO" being shown mounted on the base 51 which, if desired, may be so constructed as to embody the micro-point reflection effect. The words "For quality" may be provided on the front face of the base 51 in the manner described in connection with the words "Why not try the best?" on the base 37 in Fig. 2.

Unlike other optical effects characteristic of and important to the present invention, the micro-point effect does not depend on the enclosing panel for its success.

While the panel is typically transparent it, too, may be treated in various ways as regards color, translucency and mottled effects. For instance, the enclosing panel can often be made more attractive by being tinted with color, either over its surface or through its mass. This can be done if the degree of color saturation is not so excessive as to cancel out too large a portion of the light emitting from the interior thereof. Moreover, it should be remembered that the sum total effect should be no more opaque than the most transparent portion of the material embedded within the block which is meant to be seen by the observer. Then again, the enclosing panel can be mottled, for instance, three-dimensionally textured through its mass. Needless to say, the caution exercised in respect to color is exercised in respect to these mottled effects as well.

A variation or alternative arrangement of the invention pertains to the use of luminescent (fluorescent and phosphorescent) dyes and pigments as a substitute for the normal coloring matter. For these purposes the illumination source should be rich in ultra-violet energy and filters 41 used. These filters are mounted in grooves provided therefore in the respective brackets 22, 23 which are of such character as to absorb the visible light and pass the ultra-violet light. There exists the further possibility of a sign which combines the feature of a visible, as well as a luminescent sign. This can be done by using coloring matter which is suitable for illumination by visible light, but which also possesses luminescent properties. Needless to say, the appearance of the sign under the two different sources of illumination is markedly different. It is also to be understood that the filter 41 may be used to determine the character and color of visible light and if desired one filter may be used to provide one color and the other used to provide another different color.

There is also an additional advantage in a sign wherein the characters are embedded. When ordinary cut out block letters of substantial depth are seen from the front, or from an angle not far from the front, both the front and back of any particular letter can be seen simultaneously, i. e. the whole letter is seen at a glance. However, in the case of a sign of this type when a person moves from a position directly facing the sign the back of any given letter is cut off by

the other letters; the letters are incompletely seen and the vision is confused. This is not the case with the present sign. When the person viewing the letters moves from a position directly in front of such sign, refraction causes the letters apparently to shorten, but the whole of any letter can still be seen (within reasonable limits). Thus, the sign characters are seen in their entirety as clearly from the side as from the front. Combined are the depth and substantiality of a thick letter seen from the front and the legibility of a shallow letter seen from the side. This special characteristic results from embedding the block letters in a refracting medium.

An additional feature of the invention is the provision for the embedding of a real object, or a facsimile object, as shown in Fig. 4 wherein said object comprises a bottle 42, although other objects may be used, depending upon what is being advertised; and, of course, written or other material may be used in connection with such object.

Moreover, the shape of the panel can be made to conform to the general shape of said bottle or other object.

Another possible variation provides for the bottle or other object partly enclosed and partly outside of the panel 11, interpenetrating it as it were, and even further variations are possible.

In summary, the characteristics of the enclosing block or panel 11 need not exactly conform to those shown in the drawing. In general, however, it can be said that its face should be highly polished and that it should be of such a shape as to reflect the light internally with a high degree of efficiency directing the rays to the sign characters. For specific effects the face of the enclosing panel can be given a contour which, owing to the effects of optical refraction, results in an optical distortion of the sign characters within the block. For certain applications, i. e. decorative figures such as flowers, etc. the shape of the enclosing block may be cylindrical. Here again, however, it should be noted that the non-planar shape of such a surface gives rise to pronounced refractory effects. Such effects, however, can be highly illusory and intriguing. The panel, while normally transparent, can, as has been pointed out above, be treated in various ways, i. e. it can be three-dimensionally textured, colored, etc.

While the panel 11 may have its rear surface highly polished, and thus invisible to the observer, another method of treating said surface is shown in Fig. 3 wherein an appropriate material such as paper or cloth, on which is printed or otherwise reproduced a texture, design or pattern, is impregnated with a transparent plastic material and under heat and pressure the material is forced against the rear surface of the enclosing panel so as to become physically and optically united to it, as indicated at 43. The light rays traveling through the panel are reflected from this layer to the observer and enable the design to be seen. An advantage of this method is that the effect of almost any material or texture—cloth, metal, wood, etc.—can be reproduced. The process involved is one of lamination.

It is also to be noted that an actual material, such as a monk's cloth or a velvet, can be impregnated and then laminated to the rear surface of the enclosing block.

A grain duplicating that of coarse wood or other appropriate material can be given to the rear surface by heating and softening the rear

surface and then forcing this pattern on to it using the original grained material itself or a metal die. Or, the rear surface can be silvered so as to function like a mirror. In this way the thickness of the sign characters "ORO" can be apparently doubled owing to the reflection set up.

I claim:

1. An illuminated sign comprising: a one-piece solid molded panel of light transmitting material, said panel having a cavity therein in which a sign character comprising a solid substance of optical characteristics different from said panel is molded so as to be fully embedded within said panel and united thereto by molding whereby no interlayer of air exists between the contacting surfaces of said sign character and said panel, none of the surfaces of said sign character being coplanar with any surface of said panel thereby creating the appearance of being unattached to any surface of said panel and of being freely suspended therein, and means for illuminating said sign.

2. An illuminated sign comprising: a one-piece molded panel of light transmitting material, said panel having two cavities therein in which sign characters comprising solid substances of optical characteristics different from said panel are molded so as to be embedded within said panel and united thereto by molding whereby no interlayer of air exists between the contacting surfaces of said sign characters and said panel, one sign character having its rear surface coplanar with the rear surface of said panel and being substantially opaque relative to the other sign character, and the other sign character having none of its surfaces coplanar with any surface of said panel and positioned substantially in front of the first sign character thereby creating the appearance of being unattached to any surface of said panel and of being freely suspended therein, the sign character in front being substantially transparent and allowing the sign character in the rear to be seen simultaneously with it, and means for illuminating said sign.

3. An illuminated sign comprising: a one-piece solid molded panel of light transmitting material, said panel having a cavity therein in which a sign character of optical characteristics different from said panel is molded so as to be fully embedded within said panel and united thereto by molding whereby no interlayer of air exists between the contacting surfaces of said sign character and said panel, said sign character comprising a vehicle of transparent material in which are embedded minute particles of a transparent material of a different index of refraction from that of said vehicle, the size, number and distribution of said particles in said vehicle producing a reflection effect of great depth and intensity, none of the surfaces of said sign character being coplanar with any surface of said panel thereby creating the appearance of being unattached to any surface of said panel and of being freely suspended therein, and means for illuminating said sign.

4. An illuminated sign comprising: a one-piece solid molded panel of light transmitting material, said panel having a cavity therein in which a sign character of optical characteristics different from said panel is molded so as to be fully embedded within said panel and united thereto by molding whereby no interlayer of air exists between the contacting surfaces of said sign character and said panel, said sign character

15

comprising a vehicle of transparent material in which are located minute cavities of a gaseous transparent material of a different index of refraction from that of said vehicle, the size, number and distribution of said cavities in said vehicle producing a reflection effect of great depth and intensity, none of the surfaces of said sign character being coplanar with any surface of said panel thereby creating the appearance of being unattached to any surface of said panel and of being freely suspended therein, and means for illuminating said sign.

ROBERT W. MALLARY.
